UNITED STATES PATENT OFFICE

102,182

DESIGN FOR A SALESMAN'S DISPLAY TRAILER

Charles T. Falk, Kansas City, Mo.

Application August 24, 1936, Serial No. 64,554

Term of patent 3½ years

To all whom it may concern:

Be it known that I, Charles T. Falk, a citizen of the United States, residing at Kansas City, Jackson County, Missouri, have invented a new, original, and ornamental Design for a Salesman's Display Trailer of which the following is a specification, reference being had to the accompanying drawing, forming a part hereof.

Figure 1 is a perspective view of a salesman's display trailer showing my design as it appears in the closed position.

I claim:—

The ornamental design for a salesman's display trailer, as shown and described.

CHARLES T. FALK.
